CUTTING MECHANISM FOR FINISHING MACHINES

Max W. Winkler, Northampton, Pa., assignor to
 Queen City Textile Corporation, Allentown, Pa.,
 a corporation of Pennsylvania

Application February 18, 1936, Serial No. 64,545

49 Claims. (Cl. 26—7)

This invention relates to cutting mechanisms for trimming the edges and slitting a traveling web of warp knit fabric as the fabric is treated on the finishing machine.

5 It is the aim of the present invention to obviate the necessity of a separate machine for slitting the traveling fabric and cutting the edges thereof by combining the slitting and cutting mechanism with the conventional finishing machine on which the traveling web of fabric is dried and stretched in the same operation.

10 One of the essential features of the present invention is the arrangement of the cutting mechanism to trim the edges of the knit fabric on the finishing machine thereby leaving an even smooth edge that facilitates rolling into neat bolts which edges are customarily curled and full of pin holes from the tentering pins, and these curled edges impede the rolling of the fabric into 15 bolts.

20 In the conventional process the intermediate portions of the web of knit fabric will dry long before the edges. It is therefore another feature of the present invention to reduce the time ordinarily consumed by the finishing operation and to increase the speed of the machine by devising a construction that severs the damp edges of the fabric as it comes from the drying chamber on the finishing machine thereby saving the 25 difference in the amount of time consumed in drying the edges and the amount of time required to dry intermediate portions of the web.

30 Further objects of the present invention are to provide cutting mechanisms of the character referred to that are strong, compact and durable, very easily manipulated, thoroughly reliable for their intended purposes, adaptable to the conventional finishing machines, and comparatively inexpensive to manufacture and install.

35 With the foregoing and other objects in view the invention consists of a novel construction, combination and arrangement of parts as will be hereinafter more specifically described and illustrated in the accompanying drawings, wherein in the embodiments of the invention are disclosed, but it is to be understood that changes, variations and modifications may be resorted to without departing from the spirit of the claims hereunto appended.

40 In the drawings wherein like reference characters denote corresponding parts throughout the several views:—

45 Figure 1 is a top plan view of the delivery end of a cloth finishing machine which stretches and dries the knit fabric showing an adaptation there-

with of the cutting mechanisms of the present invention.

5 Figure 2 is an enlarged detailed vertical section taken substantially on the plane of line 2—2 of Figure 1 through one of the edge trimming members and looking in the direction of the arrows.

10 Figure 3 is an enlarged detailed vertical section through one of the edge trimming members taken substantially on the plane of line 3—3 of Figure 2 and looking in the direction of the arrows.

15 Figure 4 is a perspective view of one of the bearing housings for the cutter shaft on the edge trimming member removed from the end of the supporting arm.

20 Figure 5 is a top plan view partly in section of a shoe plate on one of the edge trimming members.

25 Figure 6 is a fragmentary diagrammatic view showing the relation of the abrading wheels with respect to the rotary cutting discs on the edge trimming members.

Figure 7 is a sectional view through the guide arm and carriage of an edge trimming member taken substantially on line 7—7 of Figure 2.

25 Figure 8 is a vertical detailed section through the lifting lever taken substantially on the plane of line 8—8 of Figure 3 and looking in the direction of the arrows.

30 Figure 9 is a detailed vertical section through the single slitting member taken substantially on the plane of line 9—9 of Figure 1 and looking in the direction of the arrows.

35 Figure 10 is a detailed vertical section through the lifting lever for the single slitting member taken substantially on the plane of line 10—10 of Figure 9.

40 Figure 11 is a top plan view of a multiple slitting member or unit shown in applied relation on a finishing machine.

45 Figure 12 is a detailed vertical section through the multiple slitting member taken substantially on the plane of line 12—12 of Figure 11 and looking in the direction of the arrows.

Figure 13 is a detailed vertical section through the drive shaft coupling on the multiple slitting unit taken substantially on the plane of line 13—13 of Figure 11.

50 Referring to the drawings in detail A indicates a finishing machine for fibrous webs such as warp knit fabrics. This machine is of conventional structure like in U. S. Patent 1,067,829, July 22, 1913 and combines the drying operation and the stretching or tentering operation in the one finishing machine as is customary in the trade.

The delivery end of the machine only is shown for the purpose of illustrating the cutting mechanisms applied thereto. Any of the conventional drying means (not shown) may be used on the machine.

The machine is formed of a pair of side frames 15 which in accordance with the conventional practice are laterally adjustable to provide the proper degree of stretch transversely of the knit fabric web 16 which travels continuously through the machine. Web 16 is dried and stretched on the finishing machine. As is the conventional construction, the endless tentering chains 17, one on each side, travel continuously at predetermined speeds in slotted, edge-wise disposed, channel guides 18, one on each side frame 15 and secured thereto. Each link of each tentering chain 17 is equipped with an inwardly directed finger 19 that extends through a slot in the channel 20 guide 18 and carries the upwardly directed tentering pins 20 on the free end. The knit fabric comes to the finishing machine in the wet condition in a relatively long web and is of a uniform width. The side edges of the web are forced over the pins 20 on the tentering chain 17 at the loading end of the machine with intermediate portions stretched between the chains. The tentering chains 17 travel under power supplied by the machine, carrying the stretched web 16 from the loading end to the delivery end of the finishing machine A where the web passes around a pair of elevated rolls 21, in a manner shown in Figures 1 and 9, from whence it travels to an overhead device (not shown) which folds the fabric.

As the web 16 passes along the machine the tentering chains progressively spread apart to stretch the fabric within certain limits, depending on the character of the fabric and other practical factors. While the fabric is being stretched the web passes through the drying chamber of conventional construction (not shown) and comes out of the drying chamber where it is acted on by the edge trimming and slitting members of the present invention which are shown in Figure 1 assembled on the delivery end of the machine.

Referring to Figure 1 where the delivery end of the machine A rearwardly of the drying chamber is shown, it will be seen that there is one edge trimming member B on one side and another edge trimming member C on the other side, both of which are in alignment with each other. These edge trimming members trim the curled edges 22 from the web of knit fabric while the web is continuously traveling on the tentering chains 17. Under certain conditions it may be desired to cut the web in half in a longitudinal direction. In this event the single slitting member D is thrown into operation. In event more than two lengths of fabric are desired, then the multiple slitting member E, shown in Figures 11, 12 and 13 is attached to the machine or moved into cooperation therewith. It is pointed out that whether the single or multiple slitting members D and E are used, the cutting discs of either are in transverse alignment with the cutting discs of the edge trimming members B and C.

Furthermore, the edge trimming members B and C are arranged to bear on top of the web 16 while the single or multiple slitting members D and E operate under the web against the bottom face thereof. As the web passes the edge trimming members B and C the severed edges 22 sticking to the tentering pins 20 wipe against the rearwardly inclined stripping plates 23 secured

to the side frames 15 and these plates strip the severed edges free of the tentering chains.

Each of the edge trimming members B and C is arranged and constructed in the same manner. It will be seen that each of the edge trimming members is carried by the tentering chain guides 18 so that in event there is any lateral adjustment of the guides it will cause a corresponding movement of the edge trimming members as a unit. In each member there is an elongated adjustable shoe plate 24 extending inwardly of the guide channels 18. This shoe plate has a pair of integral arms 25 extending outwardly provided with slots 26 through which extend the anchoring bolts 27 that fasten in the top web of the guide channels 18. The shoe plate 24 is flat but the opposite ends 28 are curved upwardly. The opposite margins of the web 16 pass under this shoe plate and an intermediate portion of the plate has an elongated slot 29 through which a segment of the rotary cutter disc extends when the disc is in cutting position as will later appear. The inside or fixed section of a pair of companion sections that form the cutter guard hood 30a has a flange 31 riveted or otherwise secured at 32 to the top face of the shoe plate 24 adjacent the slot 29. This fixed section is angular in configuration and forms the inside vertical wall 33 and rear vertical end wall 34 of the hood 30a, when the movable companion section is closed.

Each of the edge trimming members further includes an electric motor 35 anchored to an outwardly extending base plate 36 bolted to the top web of the guide channels 18. Each motor 35 has a pulley 37 on the inner end of the motor drive shaft 38. A pair of upright spaced brackets 39 have their bases secured to the base plate 36. A pivot pin 40 extends across the pair of brackets and the ends of the pin are secured in the upper portions thereof. The forward end of a cutter supporting arm 41 swings on the pin 40. Forwardly of the plate 36 is an upstanding rest or post member 42 that is fastened to the upper web of the guide channel 18. The cutter unit is supported in the inoperative position by the post 42 as is indicated in the dotted line position shown in Figure 3 of the drawings.

The rear end of each cutter supporting arm 41 has a bearing sleeve housing 43 bolted thereto as at 44. A roller bearing 45 is mounted in the housing. The ends of the rollers have pintles rotatable in the centrally apertured cap plates 46 which are secured to the ends of the sleeve housings 43. An intermediate portion of the cutter shaft 47 extends through the central apertures in the cap plates 46 and is journaled in the roller bearing 45. The outer end of each shaft 47 has a pulley 48 mounted thereon which is driven by an endless belt 49 from the motor pulley 37. On the inner end of the drive shaft 47 is the cutter disc 47a.

The movable companion section of the cutter guard hood 30a has a vertical wall 50 slotted at 51 to straddle the shaft 47 and this wall is fixed by riveting or welding to the inside cap plate 46. The vertical wall merges with the top horizontal wall 52 and the edge of this top wall in closed position bears on the top edge of wall 33 of the fixed companion section. The forward wall 53 is also integral with the wall 50. The movable section swings with the arm 41 and when the arm is down and the cutter disc 47a is cutting the cloth two companion sections form a guard hood 30a over the cutter disc. A portion

of the vertical wall 50 and the top wall 52 of the movable section is cut away to provide a recess or space 54 near the rear corner to allow the abrading wheels to engage the edge of the cutter disc 47a for the purpose of sharpening the discs. The lower segment of the cutter discs 47a registers with the slots 29 in the shoes.

The cutter discs 47a are adjustable with respect to the web of fabric being cut and also with respect to shoe plate 24. For this purpose the center of arm 41 has a screw-threaded opening to receive the intermediate portion of a threaded shank 55 on an adjusting bolt. The lower projecting end of the bolt is formed with a ball 56, which rests in a cup recess 57 on the upper face of a round plate 58 secured to the upper web of the channel guide 18. A lock nut 59 is mounted on the outer threaded portion of the shank 55 and bears on the arm 41 to lock the adjusting bolt in position. On the free upper end of the bolt is a gripping head 59a which is gripped by a wrench in adjusting the bolt.

The lower end of a rearwardly inclined guide arm 60 is riveted to the inside of the wall 50 of the movable section of the hood 30a, as at 61. The arm 60 extends through the recess 54 in the hood. On the projecting end of the guide arm slides a sectional sleeve-like carriage 62 which has a pair of integral arms 63, 64 in which are journaled a pair of abrading wheels 65, 66 made of carborundum or other like abrading material. The abrading peripheries of these wheels, 65, 66 are arranged on the opposite sides of the cutting edge of the cutter discs 47a as shown in Figure 6 of the drawings and when they are brought into engagement with the cutting edge of the disc it is dressed and sharpened.

The carriage 62 is maintained on the upper portion of the guide arm 60 in retracted position by a spring 67. One end of the spring is attached to a staple 68 on one arm 63, while the other end is anchored to the free end of the guide arm 60. To slide the carriage and abrading wheels into engagement with the cutting edges of cutter discs 47a, a lateral lever 69 is pivoted at one end at 70 to the free end of the guide arm 60. A link 71 has the lower end pivoted at 72 to the carriage 62 and its upper end pivoted at 73 to an intermediate portion of lever 69. Moving lever 69 downwardly slides the carriage and wheels into engagement with the cutting edge of the cutter discs 47a and through the recess 54 in the hood 30a, and upon the release of the lever the spring 67 retracts them to the position shown in Figure 3 and retains them in this position until force is applied to the lever 69.

To raise or lower the edge trimming members B and C free of the traveling fabric web 16 for obvious reasons, there is provided a bell crank lever having the vertex of legs 74, 75 pivoted at 76 to upstanding brackets 77 secured to the top web of the channel guide 18. The one leg 74 of the lever is upright and has a handle 78 on the free end. The free end of the other leg 75 has wiping engagement with an angle bar 79 secured to the outside of the bearing housing 43 by the screws 80. By rocking the operating lever the cutter discs 47a may be raised free of contact with the traveling web 16, and when in the rest position the cutter discs are lowered into cutting position.

It will be noted that the pivot pin 40 of the cutter shaft and supporting arm 41 is in eccentric relation with respect to the pulley 37 and

motor shafts 38 on each edge trimming member. The same is true in the single slitting member D assembly. It will be observed when the cutter discs in both assemblies are swung outwardly free of engagement with the fabric there will be slack in the belt 49 on the trimming members and on the corresponding members of the single slitting member D, which allows the cutter discs to stop revolving while the motors are still running. Then when the cutters are swung to cutting position the slack in the belt is taken up and the cutters are rotated under the power of the motors.

It will be seen that the slitting member D has a construction similar to the edge trimming members B and C except that the assembly is arranged under the web 16. To rearrange the parts to operate under the web, they are positioned and designed in a slightly different manner but the principle of operation is the same.

Now referring to the single slitting member D, it will be seen that an elongated platform 81 is secured to the machine A under the web 16 of the fabric. At one end of the platform 81 is anchored the drive motor 82 carrying a drive shaft 83 and a pulley 84. Near one end of the platform is secured an upstanding yoke 85 to the crown 85' of which is secured the rear portion of the shoe plate 86 over which the web 16 travels. The shoe plate is provided with an elongated slot 87 through which the upper segment of the cutter disc 88 extends when it is in cutting position.

The cutter shaft supporting arm 89 is pivoted at the rear end on a pivot pin 90 secured between vertical spaced brackets 91. This pivot pin 90 is also eccentric to the motor shaft 83 and the arm has a sleeve 92 embracing the pivot pin between the brackets 91.

An intermediate portion of the cutter shaft 93 of the single slitting member D is journaled in a bearing 94 on the forward end of the supporting arm 89 like in the edge trimming members B and C, but there are no cutter guards necessary since the cutter operates under the web 16 where accidents are unlikely to happen. One end of the shaft 93 is threaded and cap 94 holds the cutter disc 88 on the shaft when the nut 95 is tightened against the cap.

The arm 89 and the cutter 88 are adjustable in a manner similar to the corresponding arm and cutter discs on the trimming members B and C. A threaded shank 55' of the adjusting bolt has an intermediate portion supported in a threaded opening in an intermediate portion of the arm 89. The free upper end of the adjusting bolt bears against the bottom face of the crown 85' of the yoke 85. The lower projecting end of the threaded shank 55 extends below the arm 89 and has a gripping head thereon similar to the gripping head 59a. The locking nut 59' embracing the threaded shank 55' bears against the upper face of the arm 89 and locks the adjusting bolt in position.

The cutter supporting arm 89 swings on the pivot 90 like in the trimming members B and C but this arm 89 swings downwardly instead of upwardly. The lever that swings the arm 89 is indicated at 96 and the rear end projects rearwardly of the machine A and has a handle 97 formed thereon which is operated from the back of the machine A. The lever 96 has a certain amount of lateral flexibility for latching purposes. The forward end of lever 96 is bolted at 98 to the bearing sleeve 92 on the rear end of 75

the supporting arm 89 and the pin acts as a fulcrum for the lever as well as a pivot for the supporting arm.

Since the cutter 88 would ordinarily swing free of the cutting contact with the web 16 passing over the shoe 86, the lever 96 is secured by an upstanding latch arm 98 bolted at its lower end at 99 to an angle bar 100 mounted on a part of the finishing machine A. This latch arm 98 is positioned on the machine at approximately the middle of the lever 96. On the free upper end of the latch arm is a lateral prong 101 in the notch 102 of which seats the corner of the lever 96 when the cutter disc 88 is in cutting position.

When it is desired to move cutter disc 88 from cutting engagement with the web, as shown in Figures 9 and 10, the lever 96 is pressed downwardly and then flexed side-wise free of the notch 102 whereupon the arm 89 swinging on pivot 90 moves the cutter 88 downwardly and out of cutting engagement with the web 16. It is pointed out that the cutter disc 88 is in transverse alignment with the cutter discs 47a on the edge trimming members B and C.

It is sometimes necessary to slit the web 16 into narrow pieces that require the use of more than one cutting disc. This multiple slitting member is shown at E in Figures 11, 12 and 13. In this event a long wooden or steel plate 103 may be fastened to the finishing machine A, or the plate 103 may be supported on legs (not shown) extending to the floor. In either event, the plate 103 is supported in rigid position under the web 16 of fabric to be slit, with the cutter discs in transverse alignment with the cutter discs 47a on the edge trimming members B and C. The plate 103 is disposed transversely of the web 16. It will be understood that the multiple slitting member E is used in conjunction with the edge trimming members B and C.

Adjacent each end of the plate 103 there are aligned adjustable bearings indicated generally at 104 and 105 each of which are made with a base 106 through which extends a pair of anchor bolts 107, 108 that slide to adjusted position in opposed slots 109, 110 in the plate when the bolts are loosened. When the bolts are tightened with respect to the plate the bearing members are held in stationary position. Rising from the base 106 each bearing has an arm 111 on which are formed the bearing sleeves 112 which are in alignment with each other.

Journaled in each bearing sleeve 112 in the bearings 104, 105 are intermediate portions of stub shafts 113, the inner projecting portions of which have sockets 114 confronting each other. The opposite ends of the drive shaft 115 are slidably received in these sockets. The ends of the drive shaft 115 are secured to the stub shafts 113 in the sockets by the set screws 116 mounted near the free inner ends of the stub shafts 113. The sockets 114 allow the drive shaft to be shortened or lengthened within certain limits to accommodate the movement of the bearings 104, 105 and the cutter discs. The outer ends of each stub shaft 113 is threaded and has a cutter disc 116 mounted thereon by the nuts 117, one on each side of the cutter discs. The stub shafts 113 move with the bearings 104, 105 when the bearings are adjusted so that the cutter discs may be adjusted with respect to the width of the web. An electric motor 118 is carried by a shelf or ledge 119 which may be attached to the machine A. The motor shaft 120 has a pulley 121 connected to a pulley 122 on the drive shaft 115 by a belt 123.

For each cutter disc 116 there is a shoe plate 124 at each end of the plate 103 over which the web 16 passes in wiping engagement therewith. The shoe plates 124 are arranged under the web like the shoe plates 86 and are provided with slots similar to the slots 87 through which segments of the cutting discs 116, extend. The shoe plates are laterally adjustable to accommodate the movement of the cutter discs 116. The shoe plates are supported above the plates 103 by brackets 125 the bottoms of which are fastened to plate 103 by bolts 126 which slide in slots 127 in the plate 103 and these slots are parallel with the pairs of bearing slots 109, 110. By loosening bolts 126 the shoe plates 124 are free to slide when the cutter discs 116 are adjusted.

In the single slitting member D and the multiple slitting member E it will be seen that their assembly does not use the sharpening wheels nor the cutter guards like in the edge trimming members B and C. In the multiple slitting member E the assembly does not swing in and out of cutting engagement with the web 16. The design of the parts of the multiple slitting member provides the proper position of the cutter discs 116 with respect to the web 16 for cutting purposes.

Having thus described my invention, what I claim is:—

1. The combination with a machine carrying traveling lateral stretching means for supporting a flexible web, of an edge trimming member coacting with the web to trim a marginal portion therefrom during its passage through the machine, a web slitting member coacting with the web intermediate the side edges thereof to slit the web lengthwise, and one of said members being connected with the machine.

2. The combination with a machine carrying traveling lateral stretching means for supporting a flexible web, of an edge trimming member coacting with the web to trim a marginal portion therefrom during its passage through the machine, a web slitting member coacting with the web intermediate the side edges thereof to slit the web lengthwise, and one of said members being rockably connected with the machine.

3. The combination with a machine carrying traveling lateral stretching means for supporting a flexible web, of an edge trimming member connected with the machine and coacting with the web to trim a marginal portion therefrom during its passage through the machine, and a web slitting member connected with the machine and coacting with the web intermediate the side edges thereof to slit the web lengthwise.

4. The combination with a machine carrying traveling lateral stretching means for supporting a flexible web, of an edge trimming member and a web slitting member connected with the machine, said edge trimming member being rockable toward and away from the web, and the slitting member being adjustable to vary the position of the slit relative to the width of the web.

5. The combination with a machine carrying traveling lateral stretching means for supporting a flexible web, of a rotary edge trimming member carried by one side of the machine and coacting with the web to trim a marginal portion therefrom during the passage of the web through the machine, a rotary slitting member carried by the machine to engage the web inwardly of the edge thereof, and an adjustable support carried by the slitting member to retain said member in operative relation with the web during its passage through the machine.

6. The combination with a machine carrying traveling lateral stretching means for supporting a flexible web, of a rotary edge trimming member carried by one side of the machine and co-
 5 acting with the web to trim a marginal portion therefrom during the passage of the web through the machine, a rotary slitting member carried by the machine to engage the web inwardly of the edge thereof, and an adjustable support carried by the trimming member and the slitting member to retain said members in operative relation with respect to the web during its passage through the machine.

7. The combination of a finishing machine of the character that embodies structure for laterally stretching and drying a traveling web of fibrous material, a rotary edge trimming member swingably carried by one side of the machine adjacent the edge of the web, and a rotary slitting member carried by the machine to engage the web inwardly of the edge thereof.

8. The combination of a finishing machine of the character that embodies structure for laterally stretching and drying a traveling web of fibrous material, a rotary edge trimming member swingably carried by one side of the machine adjacent the edge of the web, a rotary slitting member carried by the machine to engage the web inwardly of the edge thereof, and power means carried by the machine to drive the rotary trimming member and the slitting member.

9. The combination of a finishing machine of the character that embodies structure for laterally stretching and drying a traveling web of fibrous material, a rotary edge trimming member swingably carried by one side of the machine adjacent the edge of the web, a rotary slitting member carried by the machine to engage the web inwardly of the edge thereof, and said rotary slitting member being adjustable axially to vary the position of the slit relative to the width of the web.

10. The combination of a finishing machine of the character that embodies structure for laterally stretching and drying a traveling web of fibrous material, a rotary edge trimming member swingably carried by one side of the machine adjacent the edge of the web, a rotary slitting member carried by the machine to engage the web inwardly of the edge thereof, and an adjustable support carried by the trimming member to retain said member in operative relation with respect to the web during its passage through the machine.

11. The combination of a finishing machine of the character that embodies structure for laterally stretching and drying a traveling web of fibrous material, a rotary edge trimming member swingably carried by one side of the machine adjacent the edge of the web, a rotary slitting member carried by the machine to engage the web inwardly of the edge thereof, said rotary slitting member being adjustable axially to vary the position of the slit relative to the width of the web, said trimming and slitting members disposed on opposite faces of the traveling web, and an adjustable support carried by the trimming and slitting members to retain said members in operative relation with respect to the web during its passage through the machine.

12. The combination of a finishing machine of the character that embodies structure for laterally stretching and drying a traveling web of fibrous material, a rotary edge trimming member swingably carried by one side of the machine

adjacent the edge of the web, a rotary slitting member swingably carried by the machine to engage the web inwardly of the edge thereof, and rockable means engageable with the trimming member and slitting member to swing said members to inoperative position.

13. The combination of a finishing machine of the character that embodies structure for laterally stretching and drying a traveling web of fibrous material, a rotary edge trimming member swingably carried by one side of the machine adjacent the edge of the web, a rotary slitting member carried by the machine to engage the web inwardly of the edge thereof, said rotary slitting member being adjustable axially to vary the position of the slit relative to the width of the web, said trimming and slitting members disposed on opposite faces of the traveling web, an adjustable support carried by the trimming and slitting members to retain said members in operative relation with respect to the web during its passage through the machine, and power means carried by the machine to drive the trimming and slitting members.

14. The combination of a finishing machine of the character that embodies structure for laterally stretching and drying a traveling web of fibrous material, a rotary edge trimming member swingably carried by one side of the machine adjacent the edge of the web, a rotary slitting member carried by the machine to engage the web inwardly of the edge thereof, said trimming and slitting members disposed on opposite faces of the traveling web, an adjustable support carried by the trimming and slitting members to retain said members in operative relation with respect to the web during its passage through the machine, and power means carried by the machine to drive the trimming and slitting members.

15. The combination with a machine carrying traveling lateral stretching means for supporting a flexible web, of an edge trimming member connected with the machine and coacting with the web to trim a marginal portion therefrom during its passage through the machine, a web slitting member connected with the machine and coacting with the web intermediate the side edges thereof to slit the web lengthwise, and said members being disposed on the opposite faces of the web.

16. The combination with a machine carrying traveling lateral stretching means for supporting a flexible web, of an edge trimming member connected with the machine and coacting with the web to trim a marginal portion therefrom during its passage through the machine, a web slitting member connected with the machine and coacting with the web intermediate the side edges thereof to slit the web lengthwise, one of said members being selectively rockable, and the members being disposed on the opposite faces of the web.

17. The combination of a finishing machine of the character that embodies structure for laterally stretching and drying a traveling web of fibrous material, a rotary edge trimming member swingably carried by one side of the machine adjacent the edge of the web, a rotary slitting member carried by the machine to engage the web inwardly of the edge thereof, said rotary slitting member being adjustable axially to vary the position of the slit relative to the width of the web, and said trimming and slitting members disposed on opposite faces of the traveling web.

18. The combination with a machine carrying

traveling lateral stretching means for supporting a flexible web, of an edge trimming member connected with the machine and coacting with the web to trim a marginal portion therefrom during its passage through the machine.

19. In a machine, the combination with a pair of traveling supporting members providing tension at an angle to the direction of travel of a web carried thereby, of an edge trimming member connected with the machine and coacting with the traveling web to trim the edge therefrom during its passage through the machine.

20. The combination of a finishing machine of the character that embodies structure for laterally stretching and drying a traveling web of fibrous material, a rotary edge trimming member swingably carried by the machine adjacent one side thereof, a slotted adjustable shoe under which the margin of the web travels carried by the machine coacting with and disposed in the path of the edge trimming member, and an adjustable support carried by the trimming member and engageable with the machine to retain the trimming member in operative relation with the web during its passage through the machine.

21. The combination of a finishing machine of the character that embodies structure for laterally stretching and drying a traveling web of fibrous material, a rotary edge trimming member swingably carried by the machine adjacent one side thereof, a slotted adjustable shoe under which the margin of the web travels carried by the machine coacting with and disposed in the path of the edge trimming member, an adjustable support carried by the trimming member and engageable with the machine to retain the trimming member in operative relation with the web during its passage through the machine, and rockable means on the machine engageable with the rotary trimming member to swing the member to inoperative position.

22. An edge trimming device for use on fabric finishing machines wherein a traveling web is operated on while the latter is under lateral tension comprising a slotted shoe adapted to be carried by the side frame of the finishing machine and under which a web of fabric travels, a supporting arm pivoted to the machine, a cutter shaft carrying a rotary cutter journaled on the supporting arm to swing into and out of engagement with the traveling web with the cutter in alignment with the slot on the shoe, and adjustable means mounted on the arm and coacting with the machine to adjust the cutter relative to the shoe.

23. An edge trimming device for use on fabric finishing machines wherein a traveling web is operated on while the latter is under lateral tension comprising a slotted shoe adapted to be carried by the side frame of the finishing machine and under which a web of fabric travels, a supporting arm pivoted to the machine, a cutter shaft carrying a rotary cutter journaled on the supporting arm to swing into and out of engagement with the traveling web with the cutter in alignment with the slot on the shoe, adjustable means mounted on the arm and coacting with the machine to adjust the cutter relative to the shoe, a guide arm connected with the supporting arm, and an abrading member slidably mounted on the guide arm for sharpening the cutter.

24. An edge trimming device for use on fabric finishing machines wherein a traveling web is operated on while the latter is under lateral tension

comprising a slotted shoe adapted to be carried by the side frame of the finishing machine and under which a web of fabric travels, a supporting arm pivoted to the machine, a cutter shaft carrying a rotary cutter disc journaled on the supporting arm to swing into and out of engagement with the traveling web with the cutter disc in alignment with the slot on the shoe, adjustable means mounted on the arm and coacting with the machine to adjust the cutter relative to the shoe, a guide arm connected with the supporting arm, abrading wheels slidably mounted on the guide arm for sharpening the cutter disc, and a lifting lever mounted on the machine and engageable with the supporting arm for moving the cutter disc out of contact with the traveling web.

25. An edge trimming device for use on fabric finishing machines wherein a traveling web is operated on while the latter is under lateral tension comprising a slotted shoe adapted to be carried by the side frame of the finishing machine and under which a web of fabric travels, a supporting arm pivoted to the machine, a cutter shaft carrying a rotary cutter disc journaled on the supporting arm to swing into and out of engagement with the traveling web with the cutter disc in alignment with the slot on the shoe, adjustable means mounted on the arm and coacting with the machine to adjust the cutter disc relative to the shoe, a guide arm connected with the supporting arm, abrading wheels slidably mounted on the guide arms for sharpening the cutter disc, a lifting lever mounted on the machine and engageable with the supporting arm for moving the cutter disc out of contact with the traveling web, a motor mounted on the machine, and operative connections between the motor and the cutter shaft.

26. The combination of a finishing machine that includes traveling tentering means for supporting a fibrous web under lateral tension during passage through the machine, a web slitting member including a drive shaft adapted for mounting on a finishing machine under the traveling web, said shaft being axially extensible, a plurality of cutter discs on the shaft, a plurality of slotted shoes carried by the machine one for each cutter disc and having the slots in alignment therewith, and means for driving the shaft.

27. In combination with a machine embodying traveling lateral stretching means for supporting a fibrous web, a plurality of shoes carried by the machine beneath the web and having an accumulative area adapted to support a portion of the web less than the width thereof, a plurality of slitting members one for each shoe carried by the machine beneath the web and coacting with the shoe to slit the traveling web, and means coacting with the slitting members to vary the position of the slits relative to the width of the web.

28. In combination with a machine embodying traveling lateral stretching means for supporting a fibrous web, a shoe carried by the machine beneath the web for supporting the fibrous web at an angle relative to the plane of travel, a rotary web slitting member carried by the machine beneath the web inwardly of the sides thereof and coacting with the shoe to slit the traveling web, and means coacting with the slitting member to vary the position of the slit relative to the width of the web.

29. In combination with a machine embodying traveling lateral stretching means for supporting

- a fibrous web, a plurality of shoes carried by the machine having an accumulative area adapted to support a portion of the web less than the width of the web, a plurality of slitting members 5 one for each shoe carried by the machine and coacting with the shoe to slit the traveling web, and means coacting with the slitting members to vary the position of the slits relative to the width of the web.
- 10 30. In combination with a machine embodying traveling lateral stretching means for supporting a fibrous web, a shoe carried by the machine for supporting the fibrous web at an angle relative to the plane of travel, a rotary web slitting member carried by the machine inwardly of the sides thereof and coacting with the shoe to slit the traveling web, and means coacting with the slitting member to vary the position of the slit relative to the width of the web.
- 15 31. The combination of a finishing machine that includes traveling tentering means for supporting a traveling web under lateral tension during passage through the machine, a web slitting member including a slotted shoe carried by the machine, an adjustable cutter shaft mounted on the machine, and a cutter disc mounted on the shaft in alignment with the slot in the shoe.
- 20 32. The combination with a machine carrying traveling lateral stretching means for supporting a flexible web, of a web slitting member connected with the machine and coacting with the web intermediate the side edges thereof to slit the web lengthwise.
- 25 33. The combination with a machine carrying traveling lateral stretching means for supporting a flexible web, of a web slitting member connected with the machine and coacting with the web intermediate the side edges thereof to slit the web lengthwise, and the slitting member being adjustable to vary the position of the slit relative to the width of the web.
- 30 34. The combination with a machine carrying traveling lateral stretching means for supporting a flexible web, of a web slitting member pivotally connected with the machine and coacting with the web intermediate the side edges thereof to slit the web lengthwise, and an adjustable support carried by the web slitting member and coacting with the machine to adjust the member relative to the plane of the web.
- 35 35. The combination with a machine carrying traveling lateral stretching means for supporting a flexible web, of a web slitting member pivotally connected with the machine and coacting with the web intermediate the side edges thereof to slit the web lengthwise, an operating lever connected with the web slitting member to swing said member on its pivot, and a keeper latch carried by the machine and coacting with the lever to lock the web slitting member in operative position.
- 40 36. The combination of a finishing machine of the character that embodies structure for laterally stretching and drying a traveling web of fibrous material, a rotary edge trimming member swingably carried by the machine adjacent one side thereof, a slotted adjustable shoe under which the margin of the web travels carried by the machine coacting with and disposed in the path of the edge trimming member, an adjustable support carried by the trimming member and engageable with the machine to retain the trimming member in operative relation with the web during its passage through the machine, 45 rockable means on the machine engageable with the rotary trimming member to swing the member to inoperative position, and abrading means carried by the trimming member for selectively sharpening the same.
- 45 37. The combination with a machine carrying traveling lateral stretching means for supporting a flexible web, of a stationary motor, a rockable rotary cutter mounted on the machine to swing on an axis eccentric relative to the axis of the motor, an endless driving connection between the motor and cutter adapted to be extended between taut and slackened positions within the rocking limits of the rotary cutter, and an abrading member movably mounted on the rotary cutter for coaction with the cutter for sharpening the same.
- 50 38. The combination with a machine carrying traveling lateral stretching means for supporting a flexible web, of an edge trimming member connected with the machine and coacting with the web to trim a marginal portion therefrom during its passage through the machine, and an abrading member movably connected with the trimming member for selectively sharpening the same.
- 55 39. A device for use on machines wherein a traveling fabric web is operated upon while under lateral tension, comprising a plurality of slotted shoes supported in juxtaposition relative to the traveling web, certain ones of the shoes being disposed adjacent each edge of the web and others therebetween, a supporting arm pivotally connected at one end with the machine one for each shoe, a rotary cutter shaft carrying a rotary cutter one coacting with each of the shoes, said shafts journaled on the supporting arms to swing into and out of engagement with the traveling web with a portion of the cutter extending through the slot in the corresponding shoe, and adjustable means mounted on the arms and cooperating with the machine to adjust the cutter relative to the web.
- 60 40. The combination with a machine carrying traveling lateral stretching means for supporting a flexible web, of a stationary motor, a rockable rotary cutter mounted on the machine in spaced relation to the motor to rock on an axis eccentric relative to the axis of the motor, and an endless driving connection between the motor and cutter adapted to be extended between taut and slackened positions within the limits of the rocking movement of the rotary cutter.
- 65 41. The combination with a machine carrying traveling lateral stretching means for supporting a flexible web, of a supporting arm pivotally connected with the machine, a power driven rotary cutter carried by the arm adapted to swing into and out of engagement with the web, lever means associated with the arm to swing the same, and latch means cooperating with the lever means to secure the arm at a certain position in the swinging path of the rotary cutter.
- 70 42. The combination with a machine carrying traveling lateral stretching means for supporting a flexible web, of a cutting mechanism comprising a motor member mounted on the machine, a rotary cutting member mounted on the machine in spaced relation to the motor, one of said members being pivoted on an axis eccentric to the other, and an endless driving connection between the members adapted to be extended between taut and slackened positions within the limits of the swinging movement of said one member.
- 75 43. In a machine, the combination with a web

propelling means applying tension at an angle to the path of travel, of a web slitting member associated with the machine and coacting with the traveling web to slit the web lengthwise during its passage through the machine, said web slitting member including a rotary cutter and a motor to drive the cutter, the rotary cutter being pivoted on an axis eccentric to the driving axis of the motor, and an endless driving connection between the cutter and the motor adapted to be extended between taut and slackened positions within the limits of the swinging movement of the cutter.

44. The combination with a machine carrying traveling lateral stretching means for supporting a flexible web, of an edge trimming mechanism, and a slitting mechanism; each of said mechanisms including a rotary cutter member mounted on the machine, and a motor member mounted on the machine, one of said members being pivoted to swing on an axis eccentric to the other on each mechanism; and an endless driving connection between the members on each mechanism adapted to be extended between taut and slackened positions within the swinging movement of said one member.

45. The combination with a machine carrying traveling lateral stretching means for supporting a flexible web, of an edge trimming device carried by the machine; said device including a rotary cutter carried by the machine, and a motor carried by the machine; a driving connection between the rotary cutter and the motor; and means to render the driving connection inoperative while the motor is running.

46. The combination with a machine carrying

traveling lateral stretching means for supporting a flexible web, of a web slitting device carried by the machine; said device including a rotary cutter carried by the machine; a motor carried by the machine; a driving connection between the rotary cutter and the motor; and means to render the driving connection inoperative while the motor is running.

47. The combination with a machine carrying traveling lateral stretching means for supporting a flexible web of an edge trimming device carried by the machine, and a web slitting device carried by the machine; each of said devices including a rotary cutter, and a motor mounted in spaced relation to the cutter; a driving connection between the rotary cutter and the motor in each device; and means to render the driving connection inoperative while the motor is running.

48. The combination with a machine carrying traveling lateral stretching means for supporting a flexible web, of an edge trimming member mounted on the machine, and a stripping plate carried by the machine to strip the trimmed edge from the stretching means after the edge has been severed from the web.

49. The combination with a machine carrying traveling lateral stretching means for supporting a flexible web, of an edge trimming member and a web slitting member connected with the machine, both of said members being mounted to rock toward and away from the web, and a stripping plate carried by the machine to remove the trimmed edge from the stretching means after the edge has been severed from the web.

MAX W. WINKLER.
